DESIGN FOR A FLASHLIGHT CASING

William W. Cargill, Madison, Wis., assignor to
Blake Manufacturing Corporation, Clinton,
Mass., a corporation of Massachusetts

Application February 21, 1938, Serial No. 75,305

Term of patent 14 years

To all whom it may concern:

Be it known that I, William W. Cargill, a citizen of the United States and residing in Madison, county of Dane, and State of Wisconsin, have invented a new, original, and ornamental Design for a Flashlight Casing, of which the following is a specification, reference being had to the accompanying drawing, forming a part thereof.

Figure 1 is a view in elevation of a flashlight casing showing my new design;

Figure 2 is an end elevational view of the casing looking from above in Figure 1;

Figure 3 is an end elevational view looking from below in Figure 1; and

Figure 4 is a transverse sectional view taken in the plane indicated by the line 4—4 of Figure 1 and looking in the direction of the arrows.

I claim:

The ornamental design for a flashlight casing, as shown.

WILLIAM W. CARGILL.
